AUTOMATIC START AND STOP DEVICE

Samuel Kohn, Bronx, N. Y.

Application November 29, 1929, Serial No. 410,420

14 Claims. (Cl. 192—118)

This invention relates to control devices, and more particularly to an automatic start and stop device especially adapted for use on phonographs designed to accommodate records of the disk type.

It is an object of the invention to provide an automatic start and stop device in which the essential elements are mounted on a common pivot.

A further object is the provision of a control device for phonographs which is adapted to satisfactorily operate when used in connection with any record of the disc type, regardless of the form of the record convolutions.

These and other objects are attained by the novel construction, combination and arrangement of parts hereinafter described and shown in the accompanying drawings, constituting a material part of this disclosure, and in which:

Fig. 1 is a bottom plan view showing the device in an off position.

Fig. 2 is a similar view showing positions assumed by parts of the device during operation.

Fig. 3 is a side elevation of the device, showing a supporting base in section.

Fig. 4 is a perspective view of an element of the device.

Fig. 5 is a plan view of a modified form employing a brake, a portion of a turn table being broken away.

Referring to Fig. 3, a base 7 has journalled therein a shaft 8, to the upper end of which is carried a tone arm 9, supporting a reproducer and stylus as commonly used on phonographs. Fixed to the lower end of shaft 8 and below the base 7 is an arm 10 having at its extremity a pin 11, the latter being adapted to enter a groove formed by the flanges 12 and 13 struck up from the arm 14 of a rocker rotatably mounted on a pivot pin 15 secured to the base plate 48. The other arm 14' of the rocker, see Fig. 1, carries a roller 16 adapted to ride up onto and bear down on the flat spring 17 to cause engagement of the contacts 18 and 19, to close a circuit through an electric motor designed to rotate shaft 20 upon which is carried the usual turn table 21 of a phonograph, adapted to accommodate records of the disc type.

Fixed to shaft 20 is a pinion 22 in mesh with a relatively large gear 23, rotatably mounted on the under side of base plate 48, the gear 23 having a downwardly extending pin 24 and a lug 25 of greater length than the pin 24 and nearer the center of the gear 23, the purpose of the lug and pin being hereinafter explained.

Rotatably mounted on pin 15 is a flat member

26' of peculiar configuration having an arm 26 provided with an arcuate edge 27, and an arm 28 having a curved edge 29.

Now, as the tone arm 9 is moved to place the stylus in the starting position on a record, the pin 11 bears against the inner side of the flange 13 to rotate the rocker clockwise, (Fig. 1) causing roller 16 to bring the contacts 18 and 19 into engagement to start an electric motor. As the playing of the record proceeds, tone arm 9 moves counter-clockwise (Fig. 1) and pin 11 rides along edge 27 at first, and is finally directed upon the curved edge 29, causing member 26' to rotate clockwise (Fig. 2). Member 26' is fixed to a collar 30 rotatably mounted on pin 15, and the collar 30 is in frictional engagement with a flat spring 31, attached to a lug 32 depending from a lever 33 (Figs. 1, 4). It will be therefore seen that rotation of member 26' will impart a similar rotation to lever 33, the latter being light in weight.

The lever 33 has an elongated slot 34 through which pin 15 passes, and an arcuate slot 35 in which is positioned a roller 36 rotatably mounted on a pin 37, which is attached to arm 28. The roller 36 has a diameter equal to the width of slot 35 at each end, the slot 35 gradually becoming wider until the point 38 is reached, where the slot is appreciably wider than the roller. By means of this construction, the lever 33 is initially held away from gear 23, but is gradually moved towards gear 23 by the movement of roller 36 in slot 35.

At a predetermined point near the completion of the play of the record, the lever 33 has been urged towards gear 23 as far as possible. In the meantime, lever 33 has been rotated clockwise, which movement is limited by the engagement of the edge 42 of a recess in the lever with a lug 43 projecting downwardly from the base plate 48, in which position the lever presents a projection 45 in the path of lug 25 and as gear 23 rotates, lug 25 sweeps lever 33 counterclockwise. However, the record is still playing and the rotation of member 26' will cause the lever 33 to again move clockwise, and projection 45 will again be placed in the path of and struck by lug 25 when it makes a complete revolution.

This periodic engagement of lugs 45 and 25 continues until the stylus has reached the last convolution of the record, which convolution is usually circular, and accordingly there will be no further advance of the tone arm, and arm 28 will remain stationary. When such condition maintains, the lever 33 will remain in a low-

ered position (Fig. 2) after being swept by the lug 25. This position of the plate, as shown in dot-and-dash lines in Fig. 2, presents the corner 46 in the path so that it will be struck by lug 25, which action rotates lever 33 further in a counterclockwise direction so that the latter will engage lug 54 attached to arm 14' and move roller 16 to a position to allow contacts 18 and 19 to disengage and open the circuit through the electric motor.

Now, when the reproducer is swung to the position beyond the turntable the pin 11 will engage the outer surface of the flange 13 and moves the rocker arm 14 until the pin engages 15 against the inner surface of a flange 12' also struck up from the arm 14 and continued movement of the tone arm to its extreme position causes the pin 11 to nest itself in the corner produced by flanges 12 and 12'.

Obviously now, when the tone arm is again brought toward the starting lines of the record, the pin 11 will again contact with and ride against the inner surface of flange 13 as before explained. However, if the tone arm be 20 moved back to initial position for any reason before the record has been completed, then the pin 11 will engage the inner surface of flange 12 and thus rock the arm so as to disengage the roller 16 from flat spring 17 and thus allow 25 contacts 18 and 19 to disengage to open the circuit.

Certain makes of disc records have the final convolution in the shape of a spiral, or eccentric in which case the tone arm is given a rapid 35 counter-clockwise movement resulting in a rapid clockwise movement of the arm 28 and the lever 33. In order that it will not be necessary to wait for the turntable to stop until the record has revolved sufficiently to cause lug 25 to sweep 40 projection 45 to present the corner 46 into the path of lug 25, a pin 24 is provided on gear 23 and the pin will engage the projection 39 on a flat spring 40 attached to an upturned portion 41 of the lever 33 to move the latter to a position to cause an opening of the circuit through 45 the electric motor.

The pin 37 is movable in a slot 47 in the base plate 48 and in a slot in the base 7, the pin having attached to its upper end a pointer 49. Now, when it is desired to render the automatic control device inoperative, the pin 37 is moved to the extreme upper end of slot 47, (Fig. 1) to move arms 26 and 28 out of the path of pin 11.

Lugs 55 and 56 are provided on the base plate 48 to serve as limit stops for the switch arm 14'.

In the modification shown in Fig. 5, the rocker is provided with an arm 14a, carrying a roller 16a adapted to ride up on a spring 51, which 60 will resiliently hold the arm 14a in that position. Fixed to the arm 14a is a rod 52 projecting upwardly through an aperture in the base 7 to a position adjacent the downturned flange on the turntable, and a leather brake shoe is 65 carried by the upper extremity of rod 52. While the record is being played, the spring 51 holds the arm 14a in a position to render the brake shoe 53 ineffective. At the completion of the record, the action of lug 25 on the corner 46 of 70 the lever 33 causes the arm 14a to be moved off of spring 51 to a position where the spring will act upon the arm 14a to cause brake shoe 53 to be forced against the flange of the turntable to stop the rotation of the latter.

The foregoing disclosure is to be regarded as

descriptive and illustrative only, and not as restrictive or limitative of the invention, of which obviously an embodiment may be constructed including modifications without departing from the general scope herein indicated and denoted 5 in the appended claims.

Having thus described my invention, what I claim as new and desire to secure by Letters Patent, is:—

1. The combination with a rotating element 10 and a swinging element, of a gear driven by the rotating element, a lug, and at least one pin carried by said gear, a lever, an electric switch and a switch arm, means on the swinging element to engage the switch arm to close the switch when 15 the swinging element is moved toward the rotating element, means on the lever for engagement with the lug to move the switch arm in the opposite direction to open the circuit upon cessation of the forward movement of the swinging element, 20 and additional means on the lever for engagement with the pin upon any increase in the normal speed of the swinging element to move the switch arm to open the circuit.

2. The combination with a rotating element 25 and a swinging element, of a gear, a lever, an electric switch and a switch arm, means on the switch arm to engage the swinging element to close the switch when the swinging element is moved toward the rotating element, and means 30 on the lever for moving the switch arm in the opposite direction to open the circuit upon cessation of the forward movement of the swinging element, and means carried by said lever for engagement with said pin upon any increases over 35 the normal speed of the swinging element to move the switch arm to open the switch.

3. In combination with a phonograph, having a tone arm, an automatic start and stop device comprising an arm associated with the tone arm 40 to follow the movement thereof, a base plate, a pivot pin fixed to the base plate, a rocker mounted on the pin and adapted to be engaged by the arm to close an electric circuit, a cam member mounted on the pin and adapted to rotate by 45 engagement with the arm, a collar on the cam member, a plate mounted on the collar, a flat spring fixed to the plate and frictionally engaging the collar to cause the plate to rotate with the cam member, a lug moving in a circular path 50 adjacent the free end of the plate and adapted to strike a projection on the plate at a predetermined time, and subsequently striking another portion of the plate when the movement of the tone arm has ceased, and a lug on the rocker engageable by the plate to cause an opening of 55 the electric circuit.

4. In combination with a phonograph having a tone arm, means controlled by the tone arm to close an electric circuit, a cam member and a 60 plate rotatably mounted on a common axis, means associated with the tone arm for rotating the cam member, frictional means connecting the member and plate to cause the plate to follow the movements of the cam member, means 65 engaging a projection on the plate to rotate the plate oppositely to the rotation of the cam member when the tone arm has reached a predetermined position, and means associated with the plate to open the electric circuit when the movement of the tone arm has ceased.

5. In an automatic start and stop device, a rotatable arm, a plate and a cam member all mounted on a common axis, means to cause the cam member to follow the movement of the arm, 75

frictional means to cause the plate to follow the movement of the cam member, means acted upon by the arm to close an electric circuit, and a movable lug adapted to engage the plate to cause it to rotate in a direction opposite to the rotation of the cam member and open the electric circuit when the movement of the arm has ceased.

6. In an automatic start and stop device, a rotatable arm, a plate and a cam member mounted on a common axis, means to cause the cam member to follow the movement of the arm, frictional means to cause the plate to follow the movement of the cam member, means acted upon by the arm to close an electric circuit, a detent extending from the surface of the plate, and a rotatable pin adapted to engage the detent to cause the plate to rotate in a direction opposite to the rotation of the cam member and open the electric circuit whenever the speed of the arm is increased over its normal speed.

7. In an automatic start and stop device, a rotatable arm, a plate and a cam member mounted on a common axis, means to cause the cam member to follow the movement of the arm, frictional means to cause the plate to follow the movement of the cam member, means acted upon by the arm to close an electric circuit, and a movable lug adapted to engage the plate to cause it to rotate in a direction opposite to the rotation of the cam member and open the electric circuit when the movement of the arm has ceased, a detent extending from one surface of the plate, and a rotatable pin adapted to engage the detent to cause the plate to rotate in a direction opposite to the rotation of the cam member and open the electric circuit whenever the speed of the arm is increased over its normal speed.

8. In combination with a swinging element and a rotating element, means for automatically starting the rotating element through movement of the swinging element, and alternative means for stopping the rotating element either automatically through any departure from the normal forward movement of the swinging element while traversing the area bounded by the initial sound groove of a record on the rotating element or through manual movement of the swinging element outwardly beyond the initial sound groove of said record.

50 9. In combination with a swinging element and a rotating element, means for automatically starting the rotating element through a movement of the swinging element and alternative means for automatically stopping the rotating element either through the cessation of move-

ment of the swinging element or through any increase over the normal forward movement of the swinging element.

5 10. The combination with a swinging element, a rotating element, and means for automatically starting the rotating element, of alternative means for stopping the rotating element automatically or manually by any departure from the normal movement of the swinging element.

10 11. In combination with a rotating element and a swinging element, a lug and a pin rotated by the rotating element, a stud, a lever loosely pivotally carried by said stud, a member frictionally associated with said lever, said member being actuated by the swinging element to 15 rotate the lever, said lever also being independently actuated to open an electric circuit alternatively when the swinging element moves forward at a speed greater than its normal speed or when the swinging element ceases to move. 20

15 12. In combination with a rotating element and a swinging element, a lug and at least one pin rotated by the rotating element, a stud, a lever loosely pivotally carried by said stud and a member frictionally associated with said lever, 25 said member being actuated by the swinging element to rotate the lever in one direction, said lever also being independently actuated in the opposite direction to open an electric circuit alternatively by the lug when the swinging element 30 ceases to move, or by the pin when the swinging element moves forward at an increased rate of speed.

13. In combination with a rotating element and a swinging element, a lug and at least one pin rotated by the rotating element, a stud, a lever loosely pivotally carried by said stud, and a member being actuated by the swinging element to rotate the lever in one direction, said lever also being independently actuated in the opposite direction to stop the rotating element alternatively by the lug when the swinging element ceases to move, or by the pin when the swinging element moves forward at an increased rate of speed. 35

14. In combination with a rotating element, 45 and a swinging element, a lug rotated by the rotating element, a stud, a lever loosely pivotally carried by said stud, a member frictionally associated with said lever, said first lever being actuated by the rotating element to move it into 50 the path of the rotating lug, the free end of the member being actuated by the normal movement of the swinging element to move the lever out of the path of the rotating lug.

SAMUEL KOHN. 55
